US00D891450S

(12) **United States Design Patent** (10) Patent No.: **US D891,450 S**
(45) Date of Patent: **** Jul. 28, 2020**

(54) **DISPLAY SCREEN OR PORTION THEREOF
WITH A GRAPHICAL USER INTERFACE**

(71) Applicant: **ConocoPhillips Company**, Houston, TX (US)

(72) Inventors: **Phil D. Anno**, Houston, TX (US); **Dave W. Glover**, Katy, TX (US); **Son V. Pham**, The Woodlands, TX (US)

(73) Assignee: **ConocoPhillips Company**, Houston, TX (US)

(**) Term: **15 Years**

(21) Appl. No.: **29/637,017**

(22) Filed: **Feb. 13, 2018**

(51) LOC (12) Cl. **14-04**

(52) U.S. Cl.

USPC **D14/486**

(58) **Field of Classification Search**

USPC D14/485-495; 345/1.1, 1.2, 2.1-2.3, 3.1, 345/902; 715/763, 810, 836, 837, 846, 715/847, 977

CLAIM

We claim the ornamental design for a display screen or portion thereof with a graphical user interface, as shown and described.

DESCRIPTION

The sole FIGURE is a front view of a display screen or portion thereof with a graphical user interface showing our new design.

The outermost broken lines illustrate a display screen or portions thereof. The remaining broken lines illustrate portions of the graphical user interface. None of the broken lines form part of the claimed design.

1 Claim, 1 Drawing Sheet
